THRESHOLD SEAL AND LOCKING DEVICE

Charles R. Hunter, Camden, N. J.

Application February 13, 1946, Serial No. 647,341

20 Claims. (Cl. 20—64)

1

This invention comprises a novel and useful carpet strip, seal and locking device and more specifically resides in a threshold for doors and the like, of novel construction.

The primary object of my invention resides in providing a novel and extremely efficient air sealing means for doors and the like, positioned between a door and its frame, and which may be embodied in a threshold.

A second object of my invention is the provision of a novel retaining means for preventing opening of the door and capable of being embodied in a threshold.

A third object of my invention is the provision of a novel, efficient and convenient foot actuated mechanism for operating a door sealing and retaining means.

A fourth object of the invention is the development of a novel, compact, efficient, foot operated locking means, for securing a sealing means and a door retaining means in operative position.

A fifth object of the invention is the construction of a device in accordance with the foregoing objects, which shall be sufficiently flat and compact as to be embodied in the conventional size of threshold.

A sixth object of the invention is the development of a device in accordance with the aforesaid objects which is adapted to fit any door or type of doorway and floor.

A seventh object of the invention is the provision of an apparatus, in accordance with the aforementioned objects which shall be composed of few members, neat and unobtrusive in appearance, sturdy and reliable in operation and withal shall be economical and inexpensive to manufacture.

An eighth object of the invention is the construction of a device in accordance with the foregoing objects, which shall have its operating mechanism fully enclosed and protected from the detrimental effects of weather, dirt and tampering.

These and numerous other important objects of the invention, which will later become apparent as the following description proceeds are achieved by my invention, one embodiment of which has been illustrated, by way of example only, in the attached drawings wherein:

Figure 1 is a plan view of the base plate, certain parts being shown in their assembled position;

Figure 2 is a perspective view of one of the end supports for the cover;

Figure 3 is a perspective view of the center cover support;

Figure 4 is a perspective view of an element;

Figure 5 is a perspective view of the oscillating bar;

Figures 6 and 7 are top plan and side elevations respectively, of an operating bar;

2

Figures 8 and 9 are top plan and side elevations respectively, of another operating bar;

Figure 10 is a perspective view of one of the cam wedges;

Figure 11 is a diagrammatic sketch of a part of the cam;

Figure 12 is a vertical section transverse the sealing bar;

Figure 13 is a transverse section on the line 10 13—13 of Figure 1;

Figure 14 is an exploded perspective view of the locking mechanism; and,

Figure 15 is a fragmentary top plan showing the locking bolt in locked position.

In the accompanying drawings the character A designates generally the cover housing of my invention, B indicates the seal actuating means, C identifies the foot operated mechanism and D defines the locking device.

Specific reference is made first to Figure 1 wherein a base plate 10, constructed of any advantageous material, including metal, and of any suitable shape and size, but in the embodiment illustrated is of the dimensions conventional with a door threshold, is secured to the floor or any satisfactory portion of a door frame as by screws or equivalent anchoring devices extending through the bores 12. The cover B of any contour adapted to the situation in which it is employed and, in this instance, conforming to the conventional shape and proportions of a threshold, is secured by means of a peripheral flange 14, gasket 16, and screws 18 to the base-plate.

Mounted centrally of the base plate is a vertical pivot 20, extending through a central aperture 22 of an actuating bar 24, see Figure 5, oscillatable thereon in a manner to be set forth hereinafter.

Adjacent one end of the base plate are sets of vertical pins 26 constituting guide means for the foot operated mechanism C, the latter comprising a pair of parallel bars 28, 30 slidable transversely of said base between said guide pins, each bar carrying a pair of appropriately spaced pins 32 for retaining the ends of a transversely swinging lever 34, see Figure 4, journaled upon the vertical axle 36. The adjacent end of the bar 24 is received between the pins 32 and beneath the end of lever 34 on the bar 28 in a manner to be subsequently made clear, whereby transverse movement of one bar 28, 30 will cause an oscillation of bar 24 about its central fulcrum 20 and also cause retrograde movement, by means of link 34, of the other lever 30, 28.

As shown more clearly upon Figure 5, the oscillating bar 24 is formed of a flat strip of material with a central transversely extending portion 38 carrying the aperture 22, and thence extending in longitudinally disposed arms 40. Adjacent one extremity, an arm has a longitudinal offset ex-60 tension 42, elevated above the base 10 a sufficient

distance to snugly overlie the bar 28 between the two pins 32. At appropriate distances from the aperture 22, each arm 40 is formed with transverse extensions 44 each having a central vertical fulcrum pin 46 and a plurality of spaced, vertical, guide pins 48.

Referring now to Figures 13 and 14, an edge portion of a door 50 is longitudinally recessed to receive the channel member 52 while the corresponding portion of the cover A is similarly recessed to provide a mating channel 54. A bar 56 loosely disposed in the full length of said slot 54 is adapted to be elevated by the oscillating bar into seating, sealing and locking engagement in channel 52 as shown by the dotted line portion of Figure 13. It will be clear that the depth of channel 52 is less than that of channel 54 and the height of bar 56, whereby the elevated bar is seated securely in both channels throughout its length.

A pair of identical cam wedges 58, shown in perspective in Figure 10, are mounted in reversed positions upon the enlarged portions 44, being loosely retained by pins 48 and by the vertical axle 46, engageable in an aperture 60 in the base of the cam. The cam consists of a base or idle portion 62, an inclined operating portion 64, a locking portion 66 and a rear inclined shoulder portion 68. In the transverse planes of the cams, the cover A has the channel member 54 transversely slotted from beneath to permit transverse travel of the wedges thereacross, the slotted parts of the channel being turned back to form lateral guide surfaces 70 and a depending guide surface 72 at each side of each cam wedge. The sealing bar is bevelled on each lower edge at 74, see Figure 12, to conform to the inclined operating surfaces 64 of the reversely positioned cams 58.

In this fully retracted position, wedges 58 abut the inner side surface of the cover A with their shoulders 68, the base portions 62 being disposed in the transverse channel slots and beneath the bar 56 in inoperative position. At this time, the bar 28 is fully extended from the cover, as shown in Figures 14 and 1, while bar 30 is fully retracted. As bar 28 is now pushed in, as by actuation from the operator's foot, the pins 32 engaging the terminal 42 oscillate bar 24 about its pivot 20 in a counter-clockwise direction causing the two wedges 58 to ride through the transverse slots in the cover plate. The operating surfaces 64 now engage shoulders 74 on opposite sides and evenly and uniformly elevate the sealing bar from recess 54 into sealing engagement with recess 52. The cam locking surfaces 56 are now disposed fully beneath the bar 56, and the latter is fully seated in the door channel 52 and the threshold channel 54 as clearly shown by the dotted line construction in Figure 13. It will be understood that the pins 46 travel in an arcuate path whose center is the fulcrum pin 20, while the wedges are restrained to rectilinear transverse reciprocation by the guide slot surfaces 70, 72. Suitable lost motion is therefore provided between the pins 46 and the cam bores 60 by forming the latter as elongated slots positioned to accommodate the arc of the pin travel, as shown diagrammatically in Figure 11, wherein 76 indicates the path of movement of pin 46.

It will be apparent that when fully elevated, the bar 56 effects the dual functions of completely sealing the space between the door and its frame and also fastens the door in closed position. If desired, the locking means D may be now activated, in a manner to be later described, as by

pressure from the toe of the operator, to lock the bar 28 from return movement, whereby pressure upon the protruded bar 30 is ineffective to oscillate the bar 24 and retract the wedges.

Attention is now directed more particularly to Figures 6-9, illustrating the construction of the operating bars. Bars 28, 30 comprise narrow flat strips having an upturned end flange portion 78 for actuation by the foot of the operator and are slidably disposed through front and rear slots of the cover plate A. This flange has plane surfaces in bar 30, but in bar 28 is provided with a transverse groove 80 upon its inner surface.

Spaced from the flange 78, bar 28 is provided with an upwardly disposed, rearwardly slanting flange 82, which is adapted to abut the outer, inclined, surface of the cover A in the extreme inward position of the bar, thus acting as a stop means for the bar and as a sealing means for the bar slot in the cover. A flange 84 is similarly disposed upon bar 30 but is continued down the sides of the bar to form ribs. Adjacent the rear toe plate 82 of each bar, an analogous flange 86 is provided, cooperating with the rear surface of the cover to form a sealing means and a stop limiting the extreme outward movement of both bars. Additional identical, inclined flanges 88 are provided intermediate each bar to form supplemental stops and sealing means, cooperating with the interior surfaces of the cover. Thus, in the forward position of bar 28, forward flange 88 abuts the cover on its front inner wall while flange 86 is engaged with the rear outer wall. When the bar is in the rear position, the flange 82 abuts the front outer wall and rear flange 88 engages the inner rear wall. By this means, both the slots of the cover are sealed at each position of the bar 28. The operation of bar 30 is similar to the foregoing. Bar 28 is provided with an intermediate boss having a vertical surface 90, suitably spaced from pin 32 to constitute therewith an actuating means for the end 42 of bar 24. Upon the boss is disposed a horizontal surface 92, in the same plane with the upper surface of member 42, the surface 92 and the top of member 42 supporting, and the spaced pins 32 guiding the end 42 of the lever 24. The bar 30 is provided with a centrally disposed lug 94 having a horizontal surface 96 in the same horizontal plane with surface 92, which receives the other end of lever 34 between the two pins 32.

As shown in perspective in Figure 4, lever 34 is provided with a centrally depressed portion 98 and horizontal arms 100 which are flatly disposed upon the surfaces 92, 96 between pins 32. As will be evident, the pins 32 and the shoulder 90 are suitably positioned to allow for the angular oscillation of the members 42 and 100. As will be further evident, the ends 100 of the member 34 have a greater movement than that of member 24 and the spacing provided between the pins 32 is therefore greater than that between a pin and the shoulder 90.

As shown in plan in Figure 1 and in perspective in Figures 2 and 3, the cover plate A is provided with end supports and a center support. Each end support comprises a U-shaped member 102 having side arms 106 snugly embracing the channel 54 and with top surfaces 108 supporting the top surface of the cover. The center support 104 has a pair of parallel, oppositely and longitudinally disposed side members 110 which snugly embrace the channel member 54 and whose top surfaces 112 support the center of the cover. A transverse web 114 connects the members 110 and has a top surface 116 underlying and supporting

the under surface of channel 54 while a lower surface 118 overlies the oscillating bar 24 and is apertured to receive the pin 20. Additional pins and apertures 120 are provided to accurately position the supporting means 102 and 104 upon the base 10. The inward lower edges of member 110 are recessed at 122 to accommodate the angular movements of bar 24 thereunder. It will now be seen that the members 102 not only reinforce the upper surface of the cover member from collapse, as when a load is placed thereon, but also embrace and reinforce against distortion the lower and side walls of the channel member 54 and in the case of member 104 also serve to retain member 24 upon its pivot 20.

Attention is now specifically directed to Figures 14 and 15 illustrating the construction of the locking means. The rim or flange 14 of the cover A is enlarged upon both sides of bar 28 to form a bolt housing 124 and a bolt keeper housing 126. Each housing has a hollow axial, aligned, passageway which is open at the top and is of cruciform cross section. This passageway extends completely through housing 124, terminates adjacent the wall 128 of housing 126, and defines four parallel, longitudinal guiding grooves, slidably receiving the four corresponding longitudinal ribs 130 of the lock bolt 132. An upper surface 134 of the top rib is flush with the upper surface of housings 124, 126, and is provided with upstanding lugs 136 comprising finger or toe actuating means for sliding the bolt in the passageway. At its outward end, housing 124 is cut away vertically, and horizontally in the same plane as the lower surface of the lateral guide grooves, whereby the lock bolt may be placed upon the cut away portion with its lower rib 130 in the lower guide groove and its lateral ribs resting upon the shoulders 138 forming continuations of the lateral guide grooves. The lock bolt may now be slid axially into the housing which is of such length as to exactly receive the lock bolt, and the lock bolt retainer 140 may now be secured in position as shown in the dotted line phantom construction 140. This retainer consists of a plug, T-shaped in cross section, the lower rib 142 filling the lower groove 144 of the housing 124 and the upper and side surfaces filling up the cut away portion to the same width and height as the rest of housing 124. A screw 146 extending through a bore 148 in member 140 and into a screw threaded aperture 150 in the flange 14 secures the retainer in position.

The operation of the lock means will now be apparent. With the parts assembled, the bolt 132 is recessed into housing 124 and the space between housings 124 and 126 is therefore entirely unobstructed. Bar 28 and, of course, bar 30 may therefore be operated at will, elevating and lowering the sealing bar 56. When, however, the bar 28 has been pressed fully inward, and its flange 82 is abutting the cover A, the bolt 132 may be slid through the passageway so that it extends across the bar 28, with its two ends engaged in the corresponding guide grooves in housings 124 and 126, as shown in Figure 15, and will be apparent from Figure 14. In this position, the lower rib 130 of the bolt is disposed between the flange 82 and the end plate 78 of bar 28, locking the bar 28 from outward movement and hence preventing the associated mechanism from releasing the sealing bar 56 from its elevated position.

From the foregoing, it will be evident that the sealing means 56 may be actuated either from

within or without a door by manipulation of the protruding bars 28, 30 without employment of the locking means D. However, when desired, the latter may be actuated as set forth above, and further activation of the mechanism is blocked until the lock is released. Usually, the lock will be disposed within the door but it will be understood that in certain uses its location upon the outside will be considered preferable.

10 It will be evident that in the foregoing embodiment, I rely upon gravity to cause retraction of the sealing bar when the actuating wedges are retracted, but it is within the purview of my invention to provide auxiliary withdrawing means such as suitable spring means or a positive connection between the actuating means and the sealing means to compel withdrawal of the latter when the bar 30 is operated.

While obviously various dimensions and proportions of parts may be resorted to in practicing the invention, I find that a very satisfactory compact and inexpensively manufactured product may be employed by forming the base, cover, flanges, channel members, actuating bar, foot 20 operated bars and lever 34 from $\frac{1}{8}$ " sheet metal, this dimension of material having satisfactory strength and being readily workable in my device.

Moreover, while I have shown the lock housings as being integral with the rim 14, it will be understood that in the interests of inexpensiveness and the advantages of mass production, I may form them as separate members, assembled later as by welding and the like.

It will thus be seen that my invention provides 35 a compact, sturdy and highly efficacious device, operable either as an air sealing means, a locking means or both, and which is easily installed, difficult to tamper with and has all its parts inclosed and protected from dirt, weather or moisture.

40 In assembling my device, the base plate 10 is first secured to the door frame, as to the floor. Then the oscillating bar and the bars 28, 30 are placed in position. The wedges, lever 34 and supports 102, 104 are now installed. The cover 45 is next installed and the sealing bar 56 placed in the threshold channel 52. The door channel 52 is now mounted. The lock bolt 132 is next inserted in the housing 124 and the retainer plug 140 secured by screw 146. Any end space between the 50 ends of the cover and base plate and the frame is now filled by driving in shims of appropriate cross section.

I claim as my invention:

1. A sealing device for a frame having an 55 opening and a movable closure therefor, comprising registering channels in said frame and closure, a sealing element received in one of said channels and elevatable into sealing engagement with both said channels, oscillatory actuating means engaging the underside of the element for elevating said sealing element into sealing position and rectilinearly reciprocable operating means movable transversely of said sealing element for controlling said actuating means.

60 2. The combination of claim 1 wherein said actuating means includes an oscillating bar underlying and movable transversely of said sealing element, connecting means operatively attaching said bar to said operating means and lifting 70 means connected to said bar and said sealing element for actuating the latter upon oscillation of said bar.

75 3. The combination of claim 2 wherein said lifting means comprises cams on said bar, said cams

engaging said sealing element at spaced points to uniformly elevate the same.

4. The combination of claim 3 wherein said cams are pivotally mounted on said bar and guide means for causing transverse rectilinear reciprocation of said cams relative to said sealing element.

5. The combination of claim 1 wherein said operating means includes a slide having actuating extremities extending beyond each side of said channel receiving said sealing element, said actuating means including a pivoted bar, a portion of said bar being operatively connected to said slide.

6. The combination of claim 5 wherein said slide is coplanar with said bar, said portion of said bar being offset and resting upon said slide.

7. The combination of claim 1 wherein said operating means includes a mechanism having parallel operating slides, opposite extremities of said slides extending from opposite sides of said frame and a centrally pivoted lever terminally connected to each of said slides for simultaneous reciprocation in opposite directions, said actuating means being operatively connected to one of said slides.

8. A threshold comprising a housing receivable in a door frame, a sealing strip receivable in said housing and slidably extensible therefrom into sealing engagement with a door, oscillatory actuating means in said housing engaging the underside of the sealing strip for elevating the same, operating means housed within and extending externally of said housing and movable transversely of said sealing strip for controlling said actuating means.

9. The combination of claim 8 wherein said housing includes a hollow body, a channel member in the top surface of said body slidably receiving said sealing strip, a plurality of supports in said body, each of said supports having a recess for receiving said channel member, one of said supports having a notch upon its lower surface, said actuating means including an oscillating bar extending through said notch.

10. The combination of claim 9 wherein said actuating means includes a bar pivotally mounted for oscillation beneath said channel member, actuators connected to said bar and sealing strip and extending into said channel member, guides for restraining said actuators to straight line motion transverse said channel member, said guides comprising depending portions of said channel members.

11. The combination of claim 10 wherein said bar is pivotally mounted intermediate its ends, said cams being on opposite sides of the bar pivot.

12. The combination of claim 11 wherein said bar includes oppositely disposed parallel arms having a transverse connecting portion, said connecting portion forming the pivot of said bar.

13. The combination of claim 12 wherein said arms have lateral projections on each side, said cams being pivoted upon said bar and rest upon such projection.

14. The combination of claim 8 wherein said operating means comprises a slide connected to said actuating means and slidably transversely through apertures in opposite sides of said housing, said slide having sealing flanges for closing said apertures and constituting stop means at each end of the travel of said slide.

15. The combination of claim 8 wherein said operating means includes a pair of slides extending transversely through said housing, a lever slidably engaging said slides for causing simultaneous and opposite reciprocation thereof, said actuating means slidably engaging one of said slides for actuation by either of said slides, guides for confining each slide to straight line motion, said lever having a pivot between said slides.

16. The combination of claim 15 wherein said actuating means has a portion resting on one of said slides, one end of said lever resting on said actuating means, said lever having its intermediate portion offset downwardly between said slides.

17. The combination of claim 16 wherein said slides are provided with steps to receive the ends of said lever, said one slide receiving said portion of said actuating means in a notch in one of said steps.

18. The combination of claim 8 wherein said operating means comprises a slide connected to said actuating means and slidably transversely through apertures in opposite sides of said housing, said slide having sealing flanges for closing said apertures and constituting stop means at each end of the travel of said slide, said sealing flanges including spaced flanges alternately engaging opposite sides of the housing at each aperture, said slide having an end flange, a bolt mounted in guide ways on the exterior of said housing, said bolt being movable across said slide between said end flange and an adjacent sealing flange to prevent complete movement of said slide inwardly of said housing.

19. The combination of claim 18 wherein said end flange is provided with a recess, there being a lateral projection on said bolt, said projection being receivable in said recess.

20. A threshold comprising a housing receivable in a door frame, a sealing strip receivable in said housing and slidably extensible therefrom into sealing engagement with a door, oscillatory actuating means in said housing engaging the underside of the sealing strip for elevating the same, operating means housed within and extending externally of said housing and movable transversely of said sealing strip for controlling said actuating means, said housing including a hollow body, a channel member in the top surface of said body slidably receiving said sealing strip, a plurality of supports in said body, each of said supports having a recess for receiving said channel member, one of said supports having a notch upon its lower surface, said actuating means including

45 an oscillating bar extending through said notch, said bar having a pivot pin, said one support overlying said bar and pivot pin and retaining the bar on said pin while permitting oscillation of said bar in said notch.

CHARLES R. HUNTER.
